Atty's.

UNITED STATES PATENT OFFICE.

ALLEN D. CLOKE, OF WARREN, OHIO, ASSIGNOR TO THE YOUNGSTOWN PRESSED STEEL COMPANY, OF WARREN, OHIO, A CORPORATION OF OHIO.

SHEET-MATERIAL-SUPPORTING STRUCTURE.

Application filed July 5, 1928. Serial No. 290,519.

This invention relates to improvements in sheet material supporting structure and is here shown as embodied in such structure particularly applicable for supporting sections 5 of wallboard, or similar thin sheet material for forming partitions, walls, ceilings, and the like.

One of the features of my invention is the provision of a simple supporting structure 10 that may be adapted to a great variety of uses. My improved supporting structure is also easy and cheap to manufacture and may be readily installed with little effort.

My improved structure also furnishes a 15 strong, durable support for a partition, wall, or ceiling.

Other features and advantages of my invention will appear more fully as I proceed with my specification.

20 In that form of device embodying the features of my invention shown in the accompanying drawings, Figure 1 is a view partly in perspective and partly in section showing, for example, a portion of a partition supported by my structure, Fig. 2 is a view taken 25 as indicated by the line 2 of Fig. 1, and Fig. 3 is a view in perspective of one of the clips forming a part of my invention.

As shown in the drawings, 10 indicates a 30 channel adapted to be placed on the floor for a partition, or on the wall for a ceiling, although the use of such a channel is optional. 11, 11 indicate posts or bars, also preferably made of channel iron, the ends 11^a of said 35 posts or bars adapted to rest in the channel 10 if one is used. If the channel 10 is not used, the ends 11^a of the posts or bars may be supported on the floor or wall in any desired manner. The use of the channel 10 40 aids in lining up the posts or bars and the edge of the partition or ceiling. When the channel 10 is used it may simply rest on the floor or it may be attached thereto in any suitable manner, or it may be attached to 45 the wall for use with a ceiling structure.

In Fig. 3 is shown one of the clips forming a part of my supporting structure. This is preferably formed out of sheet metal and comprises a U-shaped portion 12 adapted to 50 embrace the three sides of one of the bars 11. The ends of the U-shaped portion 12 are preferably bent outwardly to form side wings 12^a, 12^b, and the extreme edge of each 55 of these wings is preferably curved upwardly slightly as indicated by 12^b.

In the case of a vertical wall or partition, 13, 13, indicate pieces of sheet material, for example, wallboard, which it is desired to use in forming a partition. Such wallboard, for example, may come in rectangular sections, one of which I have shown in Fig. 1 between the two posts or bars 11, 11. These two posts or bars are preferably spaced so that they will lie against its vertical edges, and the lower edge of such piece of wallboard 60 rests on the floor inside of the channel 10, if one is used. The ends of the posts 11, 11, are supported, as from the ceiling, in any suitable manner (not shown).

To hold the sections of wallboard 13 in 70 place, a suitable number of clips are applied to each post 11. These clips are applied so that the U-shaped portion of each one embraces the post 11 with the wings 12^a lying against the surfaces of adjacent sections of 75 wallboard. The clips are turned so that such wings 12^a on alternate clips lie on one side of the wallboard and the wings of the other clips lie on the other side.

The U-shaped portion of each clip is pref- 80 erably made a little smaller than the post so that the clip may be sprung or snapped onto the post where it will be held in position by the spring of the metal.

While I have shown and described certain 85 embodiments of my invention, it is to be understood that it is capable of many modifications. Changes, therefore, in the construction and arrangement may be made without departing from the spirit and scope of the 90 invention disclosed in the appended claims, in which it is my intention to claim all novelty in my invention as broadly as possible in view of the prior art.

What I claim as new, and desire to secure 95 by Letters Patent, is:

1. A sheet material supporting structure comprising; a bar; and a plurality of removable clips embracing said bar, and each provided with two oppositely extending side 100 wings lying in substantially the same plane and adapted to bear against the faces of two pieces of sheet material arranged with their edges adjacent said bar and on opposite sides thereof, said clips being arranged so that the 105 side wings of some bear against one side of said pieces of sheet material and the side wings of others bear against the opposite sides of said pieces of sheet material.

2. A sheet material supporting structure 110

comprising; a bar substantially square in cross-section; and a removable clip having a U-shaped portion adapted to embrace said bar and provided with two oppositely extending side wings lying in substantially the same plane and adapted to bear against the faces of two pieces of sheet material arranged with their edges adjacent said bar on opposite sides thereof.

10. 3. A sheet material supporting structure comprising; a bar substantially square in cross-section; and a plurality of removable clips having U-shaped portions adapted to embrace said bar and each provided with oppositely extending side wings adapted to bear against the faces of pieces of sheet material arranged with their edges adjacent said bar on opposite sides thereof, said clips being arranged so that the side wings of some bear 20 against one face of said pieces of sheet material and the side wings of others bear against the opposite face.

4. A sheet material supporting structure as claimed in claim 1, in which the clips are 25 formed out of strips of sheet metal.

5. A sheet material supporting structure

as claimed in claim 2 in which the clip is formed out of a strip of sheet metal.

6. A sheet material supporting structure as claimed in claim 3 in which the clips are 30 formed out of strips of sheet metal.

7. A sheet material supporting structure as claimed in claim 1 in combination with a channel member in which one end of the bar is supported, said channel member also adapted to support one edge of a piece of sheet material. 35

8. A sheet material supporting structure as claimed in claim 2 in combination with a channel member in which one end of the bar is 40 supported, said channel member also adapted to support one edge of a piece of sheet material.

9. A sheet material supporting structure as claimed in claim 3 in combination with a 45 channel member in which one end of the bar is supported, said channel member also adapted to support one edge of a piece of sheet material.

In witness whereof, I have hereunto set 50 my hand this 22nd day of June, 1928.

ALLEN D. CLOKE.
